UNITED STATES PATENT OFFICE.

WILLIAM TURTON, OF NEWARK, NEW JERSEY, ASSIGNOR TO UNGER BROTHERS, OF SAME PLACE.

DESIGN FOR A CORNER-PIECE FOR POCKET-BOOKS.

SPECIFICATION forming part of Design No. 25,969, dated August 25, 1896.

Application filed July 24, 1896. Serial No. 600,445. Term of patent 3½ years.

To all whom it may concern:

Be it known that I, WILLIAM TURTON, a citizen of the United States, residing at Newark, in the county of Essex and State of New Jersey, have invented and produced a new and original Design for Corner-Pieces for Pocket-Books and Like Articles, of which the following is a specification, reference being had to the accompanying drawing, which illustrates the design.

The present design relates to metallic plates for surface application on leather goods, such as pocket-books, &c.

The design consists of a corner-piece having the straight right-angular edges A B and the rounded corner C. The surface of this plate is wrought into a design of conventionalized rococo character, the essential features being

the shell part D, crossing the corner and in harmony with the outline of the same, the reverse shell E, the shell F, projecting diagonally from the main part of the corner-piece, and the border G, having at one corner of the plate the final configuration shown at I and a flower-like final shown at J.

The essential features of the design are those above set forth.

What is claimed as new is—

The design for corner-pieces for pocket-books and like articles, substantially as herein shown and described.

WILLIAM TURTON.
